CAN AND BOTTLE OPENER

John Kenington and Cloyd Kenington, Suttle, Ala.

Application June 2, 1953, Serial No. 359,028

6 Claims. (Cl. 30—22)

This invention relates to cutlery and more particularly to a can and bottle opener of a type ordinarily adapted to be carried loosely in the pocket, on a key chain or in other desired manner, and consequently, an opener which is relatively small and of comparatively light weight.

Various articles of cutlery, including can and bottle openers, have been manufactured to be carried in the pocket but frequently these devices have had parts which would project and cause injury either to the clothing or the person, and were therefore unsatisfactory for these and other reasons.

It is an object of the invention to overcome the above difficulties and to provide a simple and inexpensive can and bottle opener small enough to be carried in the pocket and of a character which will not cause injury to the clothing or the person.

Another object of the invention is to provide a can and bottle opener having a cutting blade and a sheath or holster in which the blade is safely maintained when not in use, and with means whereby the parts are definitely maintained in operative position when in use and in inoperative protected position when not in use, so that the cutting element will be prevented from causing injury when the device is carried in the pocket and is not being used.

A further object of the invention is to provide a can and bottle opener having means for maintaining the blade in the cut being made in the can or receptacle as well as having means for preventing the undesirable spray of liquid from such can or receptacle during the opening process.

Other objects and advantages of the invention will become apparent from the following description taken in conjunction with the accompanying drawings wherein:

Fig. 1 is a perspective illustrating one application of the invention with a cutting blade in operative position;

Fig. 2, a side elevation of the device of Fig. 1 with the cutter in inoperative or stored position;

Fig. 3, a detail of the cut out blank before being folded;

Fig. 4, a side elevation of the cutter per se;

Fig. 5, a sectional view on an enlarged scale with the cutter in operative position; and

Fig. 6, a similar section of a modified form of the invention.

Briefly stated, the can and bottle opener of the present invention comprises a body or handle formed of sheet metal folded along a median line to provide for double thickness and proportionate strength, said body at one side edge adjacent its end being of a shape to engage and open a bottle and being provided along the remaining portion of that edge with a pivoted cutter for opening cans, the side of the handle being provided with a receiving socket for the blade when it is not being used and with such blade mounted in a manner to be held in operative position while it is being used and the handle being provided with an opening for attaching the device to a key chain or the like.

2

With continued reference to the drawing, a body 10 of sheet metal is folded along a median line 11 to provide a handle of double thickness, the folded body being provided with similar cut out portions 12 with a hook 13 for engaging under the edge of the cap of a bottle for removing such cap, the opposite side of the cut out portion being adapted to rest upon the top of the can while the cap is being removed. In order to pierce into and open a can, a knife or cutter is attached to the body at the same edge as the bottle opener. For this purpose the body is provided with an extension or hinge member 14 which is curved around and into a depression 15 to provide a hinge member, a cutter 16 having a slot 17 providing a pindle 18 disposed in the hinge portion of said handle.

Stops 20 projecting from the side of the pindle opposite the cutter engage the edge of the handle for limiting the movement of the blade to an arc of substantially 90°. The cutter blade includes an inclined cutting edge 21 joined to an additional tip 22 having a cutting surface approximately parallel to the pindle 18. The cutter blade is provided with an aperture 23 for permitting liquid to pass out of the slit formed in a can without spraying the operator. It will be evident that when the tip 22 is first caused to penetrate a can, such tip prevents the liquid of the can from passing outwardly and as the tip 22 is further advanced into the can, the aperture 23 on the blade 16 comes to a position where the penetrated wall of the can lies between the margins of the opening 23 thereby providing communication from the inside of the can to the outside of the can. At this time the cutter blade substantially completely closes the penetration in the can and the communication from the inside to the outside of the can must be obtained through aperture 23 and such aperture serves to deflect any liquid which might otherwise pass directly through the penetration in the can wall. The cutter blade 16 is so arranged that the unsharpened sloping edge thereof in the region adjacent the opening 23 is a close approximation to an arc of a circle with the notch 24 being the center thereof.

The handle is provided with a notch 24 for receiving the lip of the can to be opened and it will be apparent that the can opener is used by first pivoting the blade 16 to its operative position and applying the can opener to the can with the blade on the inside of the can lip and the notch 24 receiving such lip. The operator then produces a rocking motion of the cutter blade by rocking the handle, thereby causing the tip 22 to puncture the can and the cutting edge 21 to produce a slit. After one rocking motion the can opener is moved along the lip of the can until the edge 22 engages the end of the slit previously formed and another rocking motion is produced until the can lid is completely severed. The cutting edge of tip 22 serves to prevent the can opener from being moved out of the previously made slit and thereby avoids the possibility of the lid being attached to spaced points after the can opener is moved around the can.

For maintaining the cutter blade 16 in its operative full-line position or its inoperative dotted-line position as shown in Fig. 5, the interior of hinge member 14 and the pindle 18 are made of non-circular outline. The hinge member of Fig. 5 is provided with a cam surface 25 which may be a curve of substantially greater radius than that of a circular tube of the same diameter, and therefore, the relatively flat pindle 18 will be retained in either position. The hinge member 14 is sufficiently resilient to permit the slight bending thereof for this purpose. The hinge member 18 of Fig. 6 is provided with an inward projection 26 which is illustrated somewhat exaggerated for obtaining a similar result of main-

taining the cutter in either its operative or inoperative positions.

For assisting in moving the cutter from its inoperative position within recess 19 to its operative position a fingernail receiving recess 27 may be provided in the handle portion, whereby a person may insert a fingernail or a sharp instrument between the cutter 16 and the body 10 for raising the cutter to its operative position.

It will be noted that the depression 15 may be formed by a stamping operation which would result in a slightly raised rib 28 which provides additional strength to the structure and an opening 29 may be provided in the handle for attaching the device to a key chain or the like.

It will be obvious to those skilled in the art that various changes may be made in the invention without departing from the spirit and scope thereof, and therefore, the invention is not limited by that which is shown in the drawings and described in the specification, but only as indicated in the appended claims.

What is claimed is:

1. A can opener comprising a body of sheet metal folded upon itself to provide a handle of superposed panels, a cutter having an aperture therethrough and an integral pintle, a hinge strap of resilient material extending from the said edge of one of the panels pivotally embracing the pintle of said cutter, the other of said panels being provided with a recess for receiving the cutter in inoperative position, the interior of said hinge strap and the pintle being of non-circular outline and constructed to maintain the cutter in fixed position sheathed within the recess in the body or in the operative position, the said one panel being provided with an elongated indentation on the face thereof adjacent the said other panel and a rib on the other face for receiving a portion of the hinge strap and for strengthening the handle, stops on said cutter projecting beyond the pintle for engagement with the said edge of the said one panel for limiting the pivotal movement of said cutter, the said edge of said handle being provided with a can lip receiving notch between said hook and said hinge strap to provide a fulcrum about which the opener is rocked, said cutter being provided with a recess for receiving a fingernail for raising the same and said other panel being provided with a cooperating recess to facilitate the insertion of a fingernail or sharp element between the cutter and the said one panel for raising the said cutter, said body being provided with an aperture at one end for attachment to a key chain.

2. A can opener comprising a body of sheet metal folded upon itself to provide a handle of superposed panels, a cutter having an integral pintle, a curved hinge strap extending from the free edge, one panel of the handle pivotally embracing the pintle of said cutter, the other of said panels being provided with a recess for receiving the cutter in inoperative position, the interior of said hinge strap and the pintle being of non-circular outline and constructed to maintain the cutter in fixed position sheathed within the recess in the body or in the operative position, the said one panel provided with an elongated indentation on the face thereof adjacent the other panel and a rib on the other face thereof for receiving the hinge strap and for strengthening the handle, stops on said cutter projecting beyond the pintle and engageable with the free edge of the said one panel for limiting the movement of said cutter, the free edges of said panel being provided with a can lip receiving notch adjacent the cutter to provide a fulcrum about which the opener is rocked, said cutter being provided with a recess for receiving a fingernail for raising the same and said other panel being provided with a cooperating recess to facilitate the insertion of a fingernail or sharp element between the cutter and the said one panel for raising the said cutter.

3. A can opener comprising a body of sheet metal providing a handle, a cutter having an integral pintle, a curved hinge strap extending from one edge of the body engaging the pintle of said cutter, said handle being provided with a recess for sheathing the cutter in inoperative position, the interior of said hinge strap and the pintle being of non-circular outline and constructed to maintain the cutter in sheathed position within the recess in the body or in its operative position, said body being provided with an indentation for receiving a portion of the hinge strap and for strengthening the handle, stops on said cutter engageable with the said one edge of the handle for limiting the movement of said cutter, the said one edge being provided with a can lip receiving notch, said cutter being provided with a recess for receiving a fingernail for raising the same and said handle being provided with a cooperating recess to facilitate the insertion of a fingernail or sharp element between the cutter and the handle for raising the same.

4. A can opener comprising a body of sheet metal providing a handle, a cutter having an integral pintle, a curved hinge strap extending from one edge of the body engaging the pintle of said cutter, said handle being provided with a recess for sheathing the cutter in inoperative position, the interior of said hinge strap and the pintle being of non-circular outline and constructed to maintain the cutter in sheathed position within the recess in the body or in its operative position, said body being provided with an indentation for receiving a portion of the hinge strap and for strengthening the handle, stops on said cutter engageable with the said one edge of the handle for limiting the movement of said cutter, the said one edge being provided with a can lip receiving notch, said cutter being provided with a recess for receiving a fingernail for raising the same and said handle being provided with a cooperating recess to facilitate the insertion of a fingernail or sharp element between the cutter and the handle for raising the same.

5. A can opener comprising a body of sheet metal providing a handle, a cutter having an integral pintle, a curved hinge strap extending from one edge of the body engaging the pintle of said cutter, said handle being provided with a recess for sheathing the cutter in inoperative position, the interior of said hinge strap and the pintle being of non-circular outline and constructed to maintain the cutter in sheathed position within the recess in the body or in its operative position, said body being provided with an indentation for receiving a portion of the hinge strap and for strengthening the handle, stops on said cutter engageable with the said one edge of the handle for limiting the movement of said cutter, the said one edge being provided with a can lip receiving notch.

6. A can opener having a can lip engaging edge, a cutter blade mounted in spaced relation to said lip engaging edge for penetration of and cutting a wall of a filled can, said cutter blade being provided with an aperture extending transversely of the blade and located in the blade so as to pass into and out of the can through the cut formed in the can wall by the cutter whereby the pressure within the can will be relieved and the contents thereby prevented from spraying upwardly.
